INDEXIBLE MULTIPLE SPINDLE HEAD FOR
DRILLING MACHINES

Lawrence Lee Schauer, Cincinnati, Ohio, assignor
to The Cincinnati Bickford Tool Company,
Cincinnati, Oakley, Ohio, a corporation of
Ohio

Application September 22, 1931
Serial No. 564,293

4 Claims. (Cl. 77—28)

To meet the requirements of present day methods of manufacture, machine tools must be capable of attaining maximum production with minimum effort on the part of the operator. 5 Therefore, it has become common practice to equip single spindle machine tools, such for example as drilling machines, with multiple tool-heads so that a plurality of machining operations may be performed simultaneously in the time 10 previously required to perform a single operation. To facilitate the work of the operator and also to expedite production, drilling machines have been provided with vertically adjustable radial arms, capable of being swung horizontally 15 about a supporting column, and a drill head carrying a suitable tool spindle has been translatable mounted on said arm. These movements of the arm and head provide universal adjustment of the tool spindle whereby an operator quickly 20 and easily may perform drilling operations anywhere over a relatively great area of a work-piece at a single setting thereof on the work-support of the machine.

This invention has for an object to render 25 available a construction in which it is possible to utilize all the advantages of a multiple-drill head in combination with all the advantages of a radial arm drilling machine.

It will readily be perceived that if a multiple 30 drill-head of conventional form be attached to the tool-head of a radial drill in the conventional manner and the arm be swung in an arc about the column, the angular position of the drills with respect to the work-piece will be changed. 35 An object of this invention is to provide improved means whereby a radial drilling machine may be utilized, by successive operations, to drill in a work-piece, a plurality of parallel rows of holes by a single row of drills carried by a multiple drill-head. This object has been attained 40 by providing an improved mount for the multiple drill-head whereby it may be adjusted angularly relative to its support to counteract or compensate for the change in angular position 45 due to the swinging movement of the radial arm.

A further object of the invention is to provide 50 an improved indexing means for a multiple drill-head whereby the head readily may be indexed in predetermined amounts such as may be required, after a swinging movement of the radial arm of predetermined amount, to reposition a row of drills parallel to a previously drilled row of holes.

Still another object of this invention is to provide 55 improved means for balancing the weight of the multiple drill-head which will not inter-

fere with the indexing movements of the head on its support.

Other objects and advantages will be in part indicated in the following description and in part rendered apparent therefrom in connection with 60 the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, 65 of which:—

Figure 1 is a side elevation of a radial drilling machine embodying the present invention. Fig. 2 is a diagrammatic plan view of the radial arm and the drill head thereon, showing, in dotted lines, various angular positions of the arm and main tool-head, and indicating the various angular positions of the multiple tool-head to compensate for the angular adjustment of the arm. Fig. 3 is a plan view of the main drill head and the auxiliary multiple tool-head carried thereby. Fig. 4 is an enlarged side elevation, partly in 75 section, of the lower portion of the main tool head and the multiple tool-head supported 80 thereon.

Referring more specifically to the drawings, 85 the invention is disclosed as embodied in a radial drill comprising a base B, an upright column C supported thereon, a sleeve S rotatably journaled on the column, a radial arm A vertically adjustable on the sleeve, and a main drill head H supported on the arm and movable horizontally 90 therealong.

Within the drill head there is rotatably and translatable mounted a spindle 1, common to radial drills. The head also contains mechanism 95 (not shown) for transmitting to the spindle rotary and axial movements from any suitable source of power, such for example, as a motor M mounted on a rearward extension of the arm. These elements are all conventional and, therefore, detailed illustration and description thereof 100 is deemed unnecessary.

As hereinbefore stated, this invention relates to the provision of an auxiliary multiple tool-head whereby rotation and translation of the main spindle 1 simultaneously may effect the drilling of a plurality of holes in a work-piece, and so to support the auxiliary tool-head that it may be moved angularly relative to the main tool-head to compensate for angular movement of the 110

arm A about the column C. This is attained as will now be described.

To the underside of the head H, there is fixedly secured, as by bolts 2, a bracket 3 having outwardly projecting portions 4^a—4^b and a central hub 5 supporting a bearing 6 for the lower free end of the spindle 1. The portions 4^a—4^b of the bracket are formed with arcuate bearing surfaces 7^a—7^b to which are fitted the ends 8^a—8^b respectively of a plate 8 journaled on the hub 5 of the bracket, coaxial with the spindle 1. The plate 8 constitutes an adjustable support for an auxiliary multiple spindle tool-head X later to be described. The bearing surfaces 7^a—7^b may be 10 formed integral with the bracket 3 but preferably they will be provided by separate members 9 and 15 secured to the portions 4^a and 4^b of the bracket, as by bolts 11.

Secured to the plate 8, and projecting downwardly therefrom are three vertically arranged guide rods e, f and g upon which are slidably fitted bearings h, i and j formed integral with the head X. Coil springs 12, surrounding the rods e, f and g and arranged intermediate the 25 lower ends of the bearings h, i and j and nuts 13, secured upon said guide rods, normally serve to maintain the auxiliary tool-head elevated but permit it to be depressed by downward movement of the main spindle 1.

30 Within the auxiliary head X there is journaled a plurality of tool spindles 14, each adapted to carry a suitable tool t. Rotation is transmitted to the spindles 14 from the main spindle 1 by a suitable gear train designated generally as x. 35 Thus rotation and translation of the main spindle will effect simultaneous rotation and translation of all of the tools t.

As shown in the drawings, (see full lines Fig. 2) the auxiliary tool spindles are arranged in a line 40 normally parallel to the front face of the arm A. One of the objects of this invention is to provide means for drilling a plurality of parallel rows of holes in a work-piece without shifting the work-piece. This is effected, as shown in 45 Fig. 2, by simultaneously drilling a first row of holes, then swinging the arm angularly about the column and then indexing the plate 8, and the multiple tool-head carried thereby, on the bracket 3 in the direction opposite to the movement of the arm, thereby to position the tools parallel to the row of previously drilled holes. This indexing of the auxiliary head may be effected by grasping the handle 15, carried by the 50 plate 8, and swinging the plate about the axis of the spindle 1. When the series of holes are 55 to be drilled at predetermined spaced intervals means may be provided for readily determining the amount of angular movement to be given to the plate to compensate for the angular movement of the arm, and to lock the plate in its 60 adjusted position. This conveniently may comprise a spring-pressed lock-bolt 16, connected with the handle 15, and adapted to enter suitably spaced sockets 17 formed in the underside 65 of the portion 4^b of the bracket 3. It will be understood that where the plurality of series of holes are to be arranged in a straight line as indicated by the dot-dash lines w in Fig. 2, the 70 drill head will be shifted lengthwise of the arm A for each angular adjustment of the latter.

75 From the foregoing it will be perceived that I have provided an improved mount for multiple tool heads which readily permits of angular adjustment to compensate for angular movement of the arm of a radial drill.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention, and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

1. In a drilling machine provided with a column; an arm projecting radially therefrom and movable angularly thereabout, a main tool-head mounted on said arm and a main spindle rotatably and translatable journaled in said tool-head; a bracket removably secured to the lower end of said tool-head and having a hub affording a bearing for said spindle, said bracket also being provided with a plurality of locating devices; a plate rotatably journaled on said hub and supported on said bracket and indexable about the axis of said spindle; an auxiliary multiple tool-head yieldingly supported on said plate and movable axially with said spindle; a plurality of auxiliary tool spindles journaled in said auxiliary tool-head; means to rotate said auxiliary tool spindles from said main spindle; means to index said plate and auxiliary tool-head relative to said bracket; and detent means carried by said plate and cooperating with said locating devices to lock said plate to said bracket in any one of a plurality of predetermined angular positions.

2. In a drilling machine provided with a column; an arm projecting radially therefrom and movable angularly thereabout; a main tool-head mounted on said arm and a main spindle rotatably and translatable journaled in said tool-head; a bracket secured to the lower end of said tool-head, a plate rotatably journaled on said bracket and indexable about the axis of said spindle; a plurality of vertically arranged guide rods supported by said plate; an auxiliary multiple tool-head slidably mounted on said guide rods and movable axially with said spindles; yielding means tending to maintain said auxiliary tool-head elevated; a plurality of auxiliary tool spindles journaled in said auxiliary tool-head; means to rotate said auxiliary tool spindles from said main spindle; and means to index said plate and auxiliary tool-head relative to said bracket.

3. In a drilling machine provided with a column; an arm projecting radially therefrom and movable angularly thereabout, a main tool-head mounted on said arm and a main spindle rotatably and translatable journaled in said tool-head; a bracket secured to the lower end of said tool-head and comprising a central hub affording a bearing for said spindle and outwardly projecting portions formed with arcuate bearing surfaces, said bracket also being provided with a plurality of spaced sockets; a plate journaled on said hub and supported on said bearing surfaces and indexable about the axis of said spindle; an auxiliary multiple tool-head slidably supported by said plate and movable axially with said spindle; a plurality of auxiliary tool spindles journaled in said auxiliary tool-head; means to rotate said auxiliary tool spindles from said main

spindle; means to index said plate and auxiliary tool-head relative to said bracket, and a manually actuatable spring-pressed plunger carried by said plate and adapted selectively to engage said 5 sockets to hold said plate and auxiliary tool-head in their various adjusted positions.

4. In combination with a conventional radial drill having a column, an arm translatable mounted thereon, and a main tool-head translatable mounted on said arm and provided with a 10 rotatable and translatable main spindle; a completely organized unitary device removably secured upon the lower end of said main tool-head, said device comprising a bracket remov-

ably secured to said main tool-head; a plate rotatably journaled on said bracket; a plurality of vertically arranged guide-bars carried by said plate; an auxiliary tool-head slidably mounted on said guide-bars and operatively connected with said tool spindle for translation therewith; a plurality of tool spindles journaled in said auxiliary tool-head and driven from said main spindle; means permitting said plate and the elements carried thereby to be adjusted on said bracket angularly about the axis of said main spindle; and means to maintain said plate in its various positions of adjustment.
